MESNE ASSIGNMENTS, TO MORTON TRUST COMPANY, TRUSTEE, A COR-
PORATION OF NEW YORK.

MOTOR-VEHICLE.

No. 810,379.

Specification of Letters Patent.

Patented Jan. 16, 1906.

Original application filed October 23, 1899, Serial No. 734,420. Divided and this application filed September 10, 1903. Serial No. 172,563.

To all whom it may concern:

- Be it known that I, HARRY M. POPE, a citizen of the United States, residing in Chicopee Falls, county of Hampden, State of Massachusetts, have invented certain new and useful Improvements in Motor-Vehicles, of which the following is a specification, reference being had to the accompanying drawings, forming a part hereof.
- 10 This invention relates to the running-gear frames of motor-vehicles, the present application being a division of an application filed October 23, 1899, and serially numbered 734,420 for improvements in motor-vehicles.
- 15 The conditions of use of such vehicles impose requirements of construction quite different from those which have to be met in draft-vehicles. The weight of the motor and driving mechanism must be properly supported and
- 20 should be supported independently of the body of the vehicle or that portion upon which the occupants are seated. The motor, driving mechanism or connections, and driving-wheels should also be supported and connected by a rigid unyielding frame which will maintain exact alinement of the parts under all conditions. At the same time the four wheels of the vehicle must be capable of adapting themselves to a warped or uneven
- 25 road-surface, and as the steering-wheels are mounted independently upon a relatively fixed axle which stands always in a vertical plane substantially parallel with a vertical plane which includes the axis of the driving-
- 30 wheels there must be such a connection between that part of the frame which supports the motor and driving-wheels and the other part as will permit of a relative displacement of such axle and axis in such parallel vertical planes in order that the wheels may accommodate themselves to an uneven road-surface. This connection should also be of such character as to absorb to some extent the vibrations of that portion of the frame which
- 35 supports the steering-wheels or should at least prevent their transmission to the other part of the frame, while it should not be a loose connection such as would allow wear and permit rattling. The axle of the driving-wheels in particular should also be braced, so as to resist strains in a horizontal direction. In the present case it has been sought

to devise a form of running-gear frame which shall meet these several requirements, while capable of modification in form and arrangement to meet different requirements of use. 55

Figure 1 is a plan view of a running-gear frame embodying the invention, the motor-driving connections and wheels being indicated. Fig. 2 is a view in side elevation of 60 the running-gear frame shown in Fig. 1, and Fig. 3 is a detail view of a form of connecting device which may be employed between the two parts of the frame.

As represented in the drawings, the frame 65 comprises two parts or reach members, which are so connected as to permit relative oscillation or displacement about a longitudinal axis, while the two axles are held from relative displacement in a horizontal plane. One 70 of such parts supports the motor A, driving connections, and driving-wheels C always in the same relation, this part of the frame being rigid and unyielding, so as to prevent relative displacement of the several bearings 75 supported by it. The other part of the frame supports or includes the axle D, upon which are mounted the independent pivoted steering-wheels C'. The first-named part of the frame is essentially triangular, in that it has 80 three points of support or suspension—one at its apex, where connection with the other part of the frame is effected, and the other two in a line which forms the base of the triangle and corresponds with or is parallel with 85 the axis of the driving-wheels; but in actual form it may depart more or less from a triangle so far as its side members are concerned. Whenever, therefore, mention is made hereinafter of a "triangular" frame, it will be understood that such mention is made with reference to the arrangement of the points of support or suspension rather than the actual form. 90

In the construction shown in the drawings 95 the axle D of the steering-wheels C' is represented as held from displacement in the horizontal plane by connection through longitudinal springs G to the reach member D², which makes up a portion of the forward 100 part of the running-gear frame and may also be a part of the body (not shown) of the vehicle. The other part of the running-gear frame—that is, the reach member E², which

supports the motor A, driving connections, and driving-wheels C—is in actual form rather U-shaped than triangular; but the arrangement of the points of suspension is triangular, two of the points being in a line which is practically coincident with the axis E of the driving-wheels, while the other point is at the apex of this part of the frame where the connection with the other part of the frame is effected. The connecting device may be of any character which will be flexible in a vertical plane, such as that shown in detail in Fig. 3, and comprising a socket f, carried by one part and engaged by 15 a head f', carried by the other part. Springs G' are shown as secured to the reach member D² and to the rear reach member E², such construction, as will be obvious, forming a yielding connection between the two longitudinal side rods of the part D² of the frame, and therefore permitting the part D² of the frame to yield to a certain extent to accommodate itself to any unevenness in the road or to the tilting of the body. The springs G' 20 also serve to prevent displacement in a horizontal plane between the main or body-carrying part of the frame and the rear axle, and thereby to hold said rear axle substantially at right angles with the main or body-carrying part of the frame. It will 25 also be clear that other means than the springs G' might be provided to perform this function of preventing displacement between the two parts of the frame. The connecting device between the two parts of the frame is shown as supported by a cross-bar d² of the frame D².

Various modifications of the general form of the improved running-gear frame will 40 readily suggest themselves in view of the foregoing, and it is therefore to be understood that this invention is not limited to the precise arrangements shown.

I claim as my invention—

45 1. In a motor-vehicle, the combination with a motor, driving connections, driving-wheels and independent steering-wheels, of a two-part running-gear frame, one part of said frame supporting an axle which is held 50 from movement in a horizontal plane and which is provided with independent steering-wheels, the second part supporting the motor, driving connections and the driven wheels in fixed relation therewith, said second part being suspended at one point from the first-named part whereby the wheels may 55 accommodate themselves to an uneven surface without distortion of the motor and driving connections, and a spring connection 60 between the two reach members.

2. In a motor-vehicle, the combination with a motor, driving connections, driving-wheels and independent steering-wheels, of a two-part running-gear frame, each part of

which frame includes an axle member, said parts being connected to each other at a single point whereby the wheels may accommodate themselves to an uneven surface, and spring connections between the two reach members and between one of said reach members and the axle to which it is secured. 65

3. In a motor-vehicle, the combination with a motor, driving connections, driving-wheels and independent steering-wheels, of a two-part running-gear frame, each part of 70 which frame includes an axle member and a frame-like reach member extending therefrom and toward the opposite axle, and a universal connection between the sections of the running-gear frame and intermediate the 80 axles.

4. In combination in a motor-vehicle including a motor, driving-wheels, driving connections and independent steering-wheels, a running-gear frame comprising a pair of 85 axles and two frame-like reach members extending therefrom, a universal connection between the two reach members intermediate the axles, and a spring connection between the two reach members. 90

5. In combination in a motor-vehicle including a motor, driving-wheels, driving connections and independent steering-wheels, a running-gear frame comprising a pair of axles and two reach members extending from said 95 axles toward each other, one of said reach members being spring-supported upon one axle, and a universal connection between the two reach members intermediate the axles. 100

6. In combination in a motor-vehicle including a motor, driving-wheels, driving connections and independent steering-wheels, a running-gear frame comprising a pair of axles, two reach members, a universal connection between the axles, and spring connections between said reach members adjacent to one of the axles. 105

7. In combination in a motor-vehicle including a motor, driving-wheels, driving connections and independent steering-wheels, a running-gear frame comprising a pair of axles, two reach members, a universal connection between said members and intermediate the axles, spring connections between 110 said reach members intermediate the universal joint and one of the axle members. 115

8. In combination in a motor-vehicle including a motor, driving-wheels, driving connections, a non-pivotal axle, and independent steering-wheels pivoted upon said axle, a running-gear frame comprising two members supported upon said wheels respectively, one of said members carrying the motor and being pivotally mounted on the other member, said other member having intermediate 120 spring connections with the non-pivotal axle. 125

9. In combination in a motor-vehicle including a motor, driving-wheels, driving con-

- nections and steering-wheels, a running-gear frame comprising a main member supporting a body or seats, springs at the rear end of said frame and a second member carrying the motor and driving mechanism having pivotal connections at its front end with the main member and directly connected to the rear axle without the interposition of springs. 5
10. In combination in a motor-vehicle including a motor, driving-wheels, driving connections and individually-pivoted steering-wheels, a running-gear frame comprising a motor-carrying frame and a second frame having a cross-bar on which the motor-carrying frame is pivoted, and spring connections intermediate the second frame and the axles, whereby the axles are held substantially in parallelism. 15
11. In combination in a motor-vehicle including a motor, driving-wheels, driving connections and steering-wheels, a running-gear frame comprising a motor-carrying frame and a second frame having longitudinal side bars between and on which the motor-carrying frame is hung. 20
12. In combination in a motor-vehicle including a motor, driving-wheels, driving connections and steering-wheels, a running-gear frame comprising a motor-carrying frame and a second frame having longitudinal side bars and a cross-bar on which the motor-carrying frame is pivoted. 25
13. In combination in a motor-vehicle including a motor, driving-wheels, driving connections and steering-wheels, a running-gear frame comprising a motor-carrying frame supported at one end at two points, and a second frame also supported at one end at two points and at the other end upon the first-named frame, said first-named frame being pivotally hung at its other end on the second frame. 30
14. In combination in a motor-vehicle including a motor, driving-wheels, driving connections and steering-wheels, a running-gear frame comprising a frame supported at two points and a second frame also supported at two points having a cross-bar on which the first-named frame is pivoted. 35
15. In combination in a motor-vehicle including a motor, driving-wheels, driving connections and steering-wheels, a running-gear frame comprising a frame supported at two points and a second frame having longitudi- 40
- nal side bars between and on which the first-named frame is hung. 55
16. In combination in a motor-vehicle including a motor, driving-wheels, driving connections and steering-wheels, a running-gear frame comprising a frame supported at two points and a second frame having longitudinal side bars and a cross-bar on which the first-named frame is pivoted. 60
17. In combination in a motor-vehicle including a motor, driving-wheels, driving connections and steering-wheels, a main frame adapted to support the body or seats, springs supporting said main frame, a second frame carrying the motor and transmission mechanism being at its forward end pivotally connected with the main frame, and having connections with the rear axle for holding it substantially at right angles therewith. 65
18. In combination with a motor-vehicle including a motor, a rear axle, driving connections from the motor to the rear axle, a front axle, and individually-pivoted wheels thereon, a running-gear frame comprising a member supported at two points from the rear axle and carrying the motor, and a second member supported at its forward end from the front axle and extending rearwardly with reach portions projecting beside the motor-carrying member, said second member having spring connections in the rear and being adapted to carry the body of the vehicle, and said motor-carrying member extending forwardly from the rear axle between the reach portions of the second member and being supported at its forward end pivotally upon the second member. 70
19. In combination in a motor-vehicle including a motor, driving-wheels, driving connections and steering-wheels, a running-gear frame comprising two members, one member carrying the motor and pivotally connected at its front end to the other member, and springs on the forward axle supporting the combined load of the forward ends of the two members, said other member having spring connections intermediate therewith and the rear axle. 75
